UNITED STATES PATENT OFFICE.

EVERETT B. FEWELL, OF MADISON, INDIANA.

ARTIFICIAL TOOTH.

1,155,904.

Specification of Letters Patent.

Patented Oct. 5, 1915.

Application filed February 17, 1915. Serial No. 8,812.

To all whom it may concern:

Be it known that I, EVERETT B. FEWELL, a citizen of the United States, residing at Madison, in the county of Jefferson and State of Indiana, have invented a new and useful Artificial Tooth, of which the following is a specification.

The device forming the subject matter of this application is an artificial tooth and this application discloses sundry improvements over the structure shown in my prior Patent No. 1,078,844, granted on the 18th day of November, 1913.

In my prior patent above alluded to, the front of the tooth, on its rear face, is provided with a projection and a cross section taken at a proper point through the tooth front will show no less than four surfaces which must be accurately and carefully prepared, a construction which those skilled in the art will recognize at once as being difficult of attainment in practice. Further, in the structure shown in my prior patent, relative longitudinal movement in one direction between the front of the tooth and the rear portion or backing thereof is prevented by an undercut, transverse shoulder on the front. The front ordinarily is fashioned from porcelain, and it has been found difficult to produce a porcelain front the undercut transverse shoulder of which will be sufficiently accurate in configuration to serve the ends in view.

One object of the present invention, therefore, is to overcome the difficulties above mentioned.

Specifically, the present invention aims to provide a tooth front having a longitudinal bore, a portion of which is adapted to coöperate in a novel manner with an insert and with a backing, to prevent relative longitudinal movement between these parts in one direction, a portion of the bore being adapted to receive the connecting element whereby the front of the tooth is assembled with the insert and with the back.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that

changes in the precise embodiment of the invention herein disclosed can be made within the scope of what is claimed, without departing from the spirit of the invention.

In the accompanying drawings:—Figure 1 shows in longitudinal section a tooth constructed in accordance with the present invention; Fig. 2 is a perspective showing the insert; Fig. 3 is a perspective of the tooth front; Fig. 4 is a perspective of the insert, the insert being reversed from the position of figure; Fig. 5 is a longitudinal section of the front of the tooth; Fig. 6 is a longitudinal section of the front of the tooth taken in a plane at right angles to the cutting plane of Fig. 5; Fig. 7 is a longitudinal section showing a modification; Fig. 8 is a longitudinal section showing a modification; Fig. 9 is a perspective of the front as used in connection with that form of the invention which is disclosed in Fig. 8.

In carrying out the present invention there is provided a front 1 shown in detail in Fig. 3 and preferably fashioned from porcelain. The rear of the front 1 is provided with a transverse shoulder 2 above which is located a flat rear face 8. Below the shoulder 2 is located a rear face 9 which is approximately parallel to the face 8. Below the face 9, the front 1 is provided with an inclined rear face 3 defining the cutting edge of the tooth. In the front 1 is formed a longitudinal passage denoted generally by the numeral 4. That end 5 of the passage 4 which is adjacent the cutting edge of the tooth is of comparatively small diameter, whereas that end 6 of the passage adjacent the base of the tooth is of larger diameter and is located in what may be denominated the shank 7 of the tooth. It is to be observed that the rear face 8 of the front 1 of the tooth intersects the passage adjacent the base of the tooth so that the portion 6 of the passage is open, as Fig. 3 will clearly disclose.

In combination with the front 1 above described there is employed an insert shown in detail in Fig. 4. The insert comprises a body portion 10 fitting against the face 9 of the insert, an inclined flange 11 coöoperating with the face 3 of the insert, the flange 11 being provided with an opening 12 aligned with the passage 4, a shoulder 14 which engages the shoulder 2 on the front 1, a lip 15 which engages the face 8 of the front 1, and

a forwardly presented trough-like socket 16 fitting in the part 6 of the passage in the front 1, the socket 16 embodying a projecting end 40 which engages behind the shoulder 2 of the front.

The insert above described preferably is fashioned from gold and is swaged into the shape shown in Figs. 2 and 4, to conform to the rear face of the front 1.

16 After the insert has been fashioned in the manner above described, a backing 17 is built up on the insert, the backing if desired being made of gold solder or any other suitable material. This backing conforms of course to the general outlet of the insert and embodies an extension or lug 18, indicated in Fig. 1 and filling the trough-shaped socket 16 of the insert.

After the backing has been assembled 20 with the insert in the manner hereinbefore described, the insert and the backing carried thereby applied to the front 1 of the tooth and a securing or connecting device, preferably in the form of a pin 19 is passed upwardly through an opening 35 in the backing, through the opening 12 in the insert and into the portion 5 of the passage, as will be clearly understood from Fig. 1.

From the foregoing description it will be 30 obvious that the porcelain 1 is not overheated or otherwise damaged during the building up of the backing 17, since the backing is applied to the insert while the insert is separated from the front.

35 Especial attention is directed to the manner in which the extension 18 of the backing and the parts 16-40 of the insert are lodged in the open portion 6 of the passage on the front 1. Owing to the coöperation between 40 the parts above mentioned, relative transverse movement between the front 1 on the one hand and the backing 17 and the insert upon the other hand is prevented. Further, as will be obvious, longitudinal movement 45 between the parts in one direction is prevented by the construction above outlined, longitudinal movement in an opposite direction being prevented by the pin or securing element 19. Further, it is to be observed, 50 referring specifically to Fig. 3, that the rear face of the front 1 is extremely simple and presents a plurality of surfaces which may be fashioned readily without complicated grinding operations.

55 In the modification shown in Fig. 7, the parts remain substantially as above described. The front is shown at 20 and the backing appears at 21, the connecting pin being shown at 22. In this form of the invention, however, an opening 23 is made in

the transverse portion of the insert 24 and into this opening the inner end of the pin 22 extends.

In Fig. 8 of the drawings, the tooth front has been shown as assembled with a denture 65 in the form of a plate 25. The front is shown at 26 and the passage therein is of large diameter at one end, as shown at 27, of large diameter at the opposite end as shown at 28 and of a smaller diameter intermediate its ends as shown at 29. The inner end of the portion 28 of the passage forms a shoulder 30 against which abuts the end of an insert or tongue 31 carried by the plate 25. A securing pin 32 is lodged in 75 the portion 29 of the passage and the head end 33 of the pin engages the end of the insert or tongue 31. In forming the plate 25, the same is provided with a forwardly extended lug or projection 34 which co-operates with the portion 27 of the passage in the tooth front 26 as does the parts 16 and 18 of Fig. 1.

Having thus described the invention, what is claimed is:—

1. As an article of manufacture, a tooth front having a longitudinal passage, one portion of the rear face of the front being set forwardly to intersect the passage through a portion of its length and to open 90 the passage, another portion of the rear face of the front being inclined to intersect the passage.

2. In a device of the class described, a front having a longitudinal passage, a portion of the rear face of the front being set forwardly to intersect the passage and to open the same adjacent the base of the tooth; backing means comprising a transverse extension engaged in the open portion of the 100 passage; and a securing device entering the passage adjacent the working end of the front and engaged with the backing means.

3. In a device of the class described, a front having a longitudinal passage, a portion of the rear face of the front being set forwardly to intersect the passage, the front having a shoulder which extends across the passage intermediate its ends; and a backing means comprising an extension engaged in 105 the open portion of the passage, one end of the extension terminating in a projection lodged behind the shoulder.

In testimony that I claim the foregoing as my own, I have hereto affixed my signature in the presence of two witnesses.

EVERETT B. FEWELL.
